ARTHUR E. CAMBLIN, OF STELLA, NEBRASKA.

COLLAPSIBLE CORE FOR CONCRETE CULVERTS.

1,142,669.

Specification of Letters Patent.

Patented June 8, 1915.

Application filed August 16, 1912. Serial No. 715,322.

To all whom it may concern:

Be it known that I, ARTHUR E. CAMBLIN, a citizen of the United States, and a resident of Stella, in the county of Richardson and 5 State of Nebraska, have invented an Improvement in Collapsible Cores for Concrete Culverts, of which the following is a specification.

My present invention relates to collapsible 10 cores for concrete culverts, and other devices for use in concrete structures, or which are adapted to freely support mold-boards, my object being to provide a structure which may be readily and quickly collapsed and 15 withdrawn from the molded structure.

A further object of my invention is to provide a construction which will be comparatively simple and extremely inexpensive, and in which the runner and the several 20 arches may be conveniently folded so as to occupy a minimum storage space after their removal and while in disuse.

A further object of my invention is to provide a construction embodying supporting 25 arches and a runner, of which the former are capable of enlargement in a transverse direction, and adjustable with respect to the latter in a vertical direction, whereby culverts of selected proportion, with respect to 30 width and height may be formed.

With the foregoing in mind, my invention resides in the features of construction, arrangement and operation to be hereinafter described with respect to the accompanying 35 drawings, forming a part of this specification, and in which,

Figure 1 is a vertical, transverse section through a culvert illustrating the manner in which the same is supported while drying 40 and hardening by my improved core structure shown in connection therewith; Fig. 2 is a vertical longitudinal section taken there- 45 through substantially on the line 2-2 of Fig. 1; Fig. 3 is a similar view taken there- through substantially on the line 3-3 of Fig. 1 illustrating the arches folded for withdrawal; Fig. 4 is a view similar to Fig. 1, illustrating the adjustability of the arches whereby to form a culvert of greater width; 50 Fig. 5 is a detail perspective view of one of the arches removed; and Fig. 6 is a similar view of a portion of the runner.

Referring now to these figures, I provide a core structure which, as usual, consists of a 55 series of vertical transverse structures, commonly known as arches, and the edges of

which are adapted to support the longitudinal extending mold-boards A, which in practice are freely disposed thereon, and are in turn adapted to support the tamped concrete 60 mixture B which, after drying and hardening and the removal of the entire core structure including the arches and mold-boards, forms the culvert.

My invention resides in part in the specific construction of the arches, one of which is shown in detail in Fig. 5 as comprising an upper section C and a lower section C', these sections being hingedly connected at c, along their contiguous edges, and the upper 70 section being usually of semi-circular form in order to provide a culvert of rounded shape. The lower arch section C' is provided with a lower beveled longitudinal edge at the ends of which are secured protecting 75 plates c', and said section is further provided with a vertical transverse slot or opening c² extending partially therethrough from its lower edge and at a substantially 80 central point, along the sides of which slot or opening are arranged cleats c³, provided with aligned transverse apertures c⁴ at their lower end. Arranged upon one face of the upper section C is a supplemental section C², said supplemental section being of substantially 85 the same size and shape as the main upper section C, and being provided with an elongated slotted opening c⁵ formed therethrough and extending therein parallel with its lower straight edge. As clearly indicated in the several figures, the slot c⁵ receives a bolt c⁶ extending from the main upper section C of the arch, whereby the 90 said sections C and C² may be secured together in selected adjustment, that is, they 95 may be secured in registry as illustrated in Fig. 1, or they may be adjusted and secured in the position shown in Fig. 4, wherein the supplemental section C² extends to one side of the main section C for the purpose of 100 supporting the substantially widened molding structure, in the latter connection, the outer end of the supplemental section C² being supported by a vertical beam c⁷, and the inner end thereof being supported by the 105 upper ends of the cleats c³.

My invention also consists in part in the structure of the supporting runner, a portion of which is shown in detail in Fig. 6, and which is made up of a plurality of sections D-D', these sections being similar in construction and being pivotally connected 110

at their contiguous ends by connecting members *d* in such a manner that they may, in use, be extended in longitudinal alinement and may be disconnected from one another 5 after use, by simply removing the pivot bolt forming their connection, whereby they are adapted to occupy only a minimum space and also whereby it may be used in connection with the formation of a curved culvert 10 and readily removed from the curved part thereof.

At equidistantly spaced points, the runner sections D—D' are provided with a vertical series of openings *d'*, these openings 15 being adapted for the reception of a coupling pin *E*, by which each of the separate arches is connected thereto, said coupling pin *E* being adapted for passage through the cleat openings *c'* and through a selected 20 opening of the runner series *d'*, whereby the parts may be secured in selected vertical adjustment. The connection thus described is adapted to be made after the arches have been disposed on the runner by means of the 25 slots *c*² of their lower sections C'.

With the parts secured as thus described, and as particularly shown in Figs. 1 and 2, supporting blocks *F* which are flexibly attached to the lower arch sections C', are disposed beneath the lower edge of the lower arch section C', whereby to form side supports. The arches are secured in selected 30 vertical adjustment with respect to the runner which extends along the surface of the ground, and the position of the supplemental arch section C² is regulated so as to provide a culvert of selected width. After this, the mold boards A are placed in position as shown, and the material placed and properly 35 tamped in position. After the molding material has become dry and thoroughly hardened, it is necessary to remove the arches and runner, and to this end it will be noticed that longitudinal movement of the runner embodying its several sections, is such as 40 to move the lower arch sections C' to angular positions with respect to the upper sections C, thus breaking their hinged joint at *c* and causing the upper sections C to be lowered in substantially the position shown in Fig. 3. This movement results in withdrawing 45 all support from the mold-boards A and permits the latter to fall and be withdrawn, and also lowers and folds the arches in such 50 position that continued longitudinal movement of the runner will effect their withdrawal entirely from the molded culvert.

Inasmuch as the runner, the sections D and D' of which normally form supports for 55 the several arches, extends along the ground, its sliding movement for the purpose of breaking up and withdrawing the core, is a comparatively easy one, and it will be further noted that the pivotal connections of 60 the lower arch sections C' with said runner,

and also the beveled bearing surfaces of the lower arch sections upon their supporting blocks *F*, are such as to permit of ready angular movement of said lower arch sections for purposes of removal, as before described. 70

Attention is further called to the fact that in practical use, inclined supports G are employed and extend from the surface of the ground to the lower portions of the upper 75 arch sections C, these supports G being adapted to receive the lower of the series of the mold-boards A, thus leaving the lower arch sections C' absolutely free of contact with the mold-boards, and thus free for 80 angular swinging movement when the runner is moved longitudinally.

I claim:—

1. A collapsible culvert core, embodying a runner, and a plurality of arches supported on the runner and adapted to receive mold-boards, each of said arches comprising upper and lower sections which are hingedly connected to one another, and a supplemental section carried by the said upper section and laterally adjustable with respect thereto, and coöperating means for vertically adjustably connecting the lower arch section to the said runner. 90

2. A collapsible culvert core, embodying a runner having vertical series of openings at spaced points, and a plurality of arches supported on the runner and adapted to receive molding boards, each of said arches comprising an upper section and a lower 100 section hinged to the upper section and provided with a slot adapted to receive the runner, cleats arranged alongside the said slot and provided with transverse openings, and a member for engagement through said 105 cleat openings and through a selected opening of one of the runner series of openings whereby to secure the arch in selected vertical adjustment with respect to the runner. 95

3. A collapsible culvert core, embodying a runner, and a plurality of arches supported on the runner and adapted to receive mold-boards, each of said arches comprising upper and lower sections hingedly connected along their contiguous edges, and a supplemental section which is carried by the said upper section and laterally adjustable with respect thereto. 110

4. A collapsible culvert core, embodying a runner, and a plurality of arches supported on the runner and adapted to receive mold-boards, each of said arches comprising upper and lower sections hingedly connected along their contiguous edges, and a supplemental section of substantially similar 120 size and shape to said upper section, said supplemental section being provided with an elongated horizontal slot, and a clamping bolt extending from the said upper section 125 and through said slot of the supplemental 130

section whereby to secure the latter in selected lateral adjustment with respect to the former.

5. A collapsible culvert core, embodying a plurality of collapsible arches adapted to receive and support mold boards, a runner extending beneath the entire series of arches and supporting the same, and adjustable detachable connections between said arches and 10 said runner, said runner being formed in longitudinally alined sections having detachable connections at their meeting ends.

6. A collapsible culvert core, embodying a runner and a plurality of arches supported 15 on the runner and adapted to receive mold boards, each of said arches comprising upper and lower sections hingedly connected along their contiguous edges, and a supple-

mental section of substantially similar size and shape to said upper section, said supplemental section and the upper section being provided with relatively engaging means whereby the former may be maintained in selected lateral adjustment with respect to the latter, and said lower section being provided with cleats on one face forming supports for the inner portion of the supplemental section when the latter is adjusted laterally, and a vertical beam for supporting the lateral portion of the supplemental section in laterally adjusted position, all substantially as and for the purpose set forth.

ARTHUR E. CAMBLIN.
